UNITED STATES PATENT OFFICE.

FRANK A. BEMIS, OF DANE, WISCONSIN.

TRANSPLANTER.

SPECIFICATION forming part of Letters Patent No. 423,724, dated March 18, 1890.

Application filed November 20, 1889. Serial No. 330,970. (No model.)

To all whom it may concern:

Be it known that I, FRANK A. BEMIS, a citizen of the United States, and a resident of Dane, in the county of Dane and State of Wisconsin, 5 have invented certain new and useful Improvements in Transplanters; and I do hereby declare that the following is a full, clear, and exact description of the invention, which will enable others skilled in the art to which it 10 appertains to make and use the same.

My invention relates to machines for transplanting plants, such as tobacco, cabbage, and the like; and it consists more particularly in certain improvements upon my application for Letters Patent filed June 15, 1889, Serial No. 314,385, which said improvements will more fully appear in the following description and by reference to the drawings forming part of this specification, in which—

20 Figure 1 is a side elevation. Fig. 2 is a similar view of the opposite side with the wheel removed. Fig. 3 is a longitudinal vertical sectional view. Fig. 4 is a plan view looking from the under side. Fig. 5 is a cross-sectional view. Fig. 6 is a view of the inner side of one of the wheels, showing the mechanism for operating the levers which control the flow of water; and Fig. 7 is a detail view.

Similar letters of reference refer to similar 30 parts throughout the several figures.

Referring to the accompanying drawings, the letter A indicates the frame of the machine mounted upon suitable wheels B B'. This frame has projecting forwardly therefrom 35 from an arm C, said arm being provided upon its extreme forward end with bearing-plates D, in which is pivoted upon a transverse bolt E the rear end of the tongue F. This frame has also extending laterally from one 40 side metallic strips G G, the outer ends thereof being bent into angular form, and into which angular-bent ends are journaled anti-frictional wheels H H.

Depending from the under side of the front 45 cross-piece of the frame are eyebolts I I, in which turns a transverse shaft J. The ends of this shaft pass through the diverging front ends of the supporting-bars K, one of said bars being formed or provided with an upwardly-extending treadle L, which serves the 50 purpose of effecting the lifting or elevation of the plow by a pressure of the foot whenever

this is found necessary. The supporting-bars extend rearwardly and converge so as to run parallel. Suitably secured between these 55 supporting-bars is the plow or runner M, said plow or runner being provided on one side and at its end with an inclined or obliquely-extending piece N, thereby forming an approximately-wedge-shaped portion at the 60 rear end of the plow. The supporting-bars are also provided on each side with angular brackets O, to which are secured the shoes P and P', said shoes having their outer edges flanged or turned down, so as to deflect the 65 soil inwardly. It will be observed that the plate P', adjacent to the inclined side of the plow, is somewhat longer than the opposite shoe P; but they may be of equal length. The brackets above referred to are provided 70 upon their vertical members or arms with elongated slots o, a transverse pin o' first passing through the slot in one bracket, through registering perforations in the supporting-bars, and thence through the elongated slot in the bracket upon the opposite supporting-bar. In this manner the brackets are made adjustable, and being attached to the shoes the latter may be readily raised or lowered. An adjustable spring Q is secured 75 at its rear end to the upper edges of the supporting-bars and has the function of allowing the plow M to go up and down and adapt 80 itself to uneven surfaces, and also can be utilized to regulate the depth of the furrow. 85

The forward end of the plow, it will be observed, is provided with a series of perforations. This forward perforated end is designed to pass between the supporting-bars at the point where the forward brackets are 90 arranged upon the sides thereof. The perforations, therefore, will register with the elongated slots of said brackets and also with the perforations of the supporting-bars, and by means of one of the transverse pins o', here- 95 before referred to, this end of the plow may be conveniently regulated and adjustability given thereto.

The machine is also provided with rear 100 seats R R, upon which the persons depositing the plants sit. Forward rods S S extend downwardly from the front of the machine, and their lower ends are bent at an angle and provided with gathering-wings T T. A yoke

U is passed over the end of the forwardly-extending arm C, and a transverse shaft V passes through the lower ends thereof and also through the angles of the downwardly-extending rods S S. Upon this shaft is journaled a gage-wheel W. The upper end of this yoke is engaged by an adjustable ratchet-lever X, so that the height of the same may be regulated.

10 The letter Y indicates a transverse rotatable shaft, which is journaled in suitable bearings upon the under side of the side pieces of the frame and has its ends extending out beyond said bearing-points, one end being provided with an upwardly-extending bifurcated arm Z, while near the opposite end is secured an angular bracket A', the upper arm of said bracket being provided with a laterally-extending pin B'. Upon the same side 20 of the frame and to the rear is secured a bracket C', having its rear downwardly-extending member or arm provided with a series of perforations c.

The letter D' indicates a lever, the forward end of which, when actuated, being adapted to engage with the laterally-extending pin of the bracket A', and thus rotate the transverse shaft to which this bracket is attached. The rear of this lever is curved slightly downward and has pivoted thereto an arm E', said arm being provided with a perforation e, registering with the perforations of the bracket C' and also provided with an end finger-piece e'. It will also be seen that the wheel B is provided at suitable intervals with inwardly-extending pins b, which, when said wheel is revolved, engage with the curved end of the lever D', thereby depressing the forward end of said lever and turning the forward rotatable shaft by means of the laterally-extending pin projecting from the bracket secured to said shaft.

The letter F' indicates a reservoir or water-tank suitably secured to the frame of the machine, and has extending therefrom a flexible tubing G', said tube being surrounded near its nozzle by a globular collar or valve g, said collar or valve being also provided with an intersecting aperture g'. The nozzle 50 of the tube passes down between the diverging rear ends of the runner or plow, so as to direct the stream of water properly within the furrow. A downwardly and inwardly extending arm H' depends centrally from the shaft Y and has secured thereto the bent end of a rod or valve I', said rod extending rearwardly and passing through the intersecting aperture of the valve. It will thus be seen that when the shaft Y is turned in the 55 manner previously described the centrally depending arm H' is drawn forward and carries with it the valve or rod, which, being thus drawn out from the aperture in the valve, leaves a clear space for the water. A spring 60 J' has one end thereof attached to the lower end of the centrally-depending arm H', while its inner end is suitably secured to the arm

of one of the forward brackets of the supporting-bars. The resiliency of this spring serves the purpose of drawing back the arm 70 to its normal position, which in turn rotates the shaft back to its original position. By this construction an automatic and intermittent flow of water is attained. In order to regulate the length of time this flow shall be 75 continued, I have provided the series of perforations in the bracket C' and the registering perforation in the end of the arm E'. This arm E' being pivoted to the lever D', it is evident that the higher up the said arm is 80 adjusted the more depressed the rear end of the lever will be and the nearer it will approach a horizontal position. When this is the case, of course the pins extending inwardly from the wheel B will act against the 85 curved portion of the lever for a longer period than if the lever were adjusted to a higher position, and, thus acting for a considerable time, the forward end of the lever will turn the transverse shaft which actuates the valve 90 or rod and maintain a free passage of water as long as said shaft is held in its turned position. When the arm E' is adjusted to a lower position, of course the rear end of the lever is forced upward at an incline. When 95 in this inclined position, the pins escape from contact with the lever much sooner than when the same is in a lower position, and a less flow of water, or a flow for a shorter period of time, is consequently obtained. In this manner a convenient and effective means is provided for controlling the escape of water from the reservoir.

The letter K' indicates a knotted wire similar in all respects to the wires employed in 105 connection with check-rowers. This wire first passes over the forward roller or wheel H, journaled in the end of the metallic strip G, thence passes into the bifurcated arm Z, and is continued rearwardly over the rear roller 110 or wheel. As the machine traverses the ground, it is evident that the knots in the wire will, when engaged by the bifurcated arm, throw said arm rearward, and thus turn the shaft to which it is attached. The upper ends 115 of the bifurcated arm, however, being diverged or flaring, continued pull on the wire will release the same, and the shaft will thus be permitted to return to its former position. This construction therefore provides a supplemental or additional means for actuating 120 the shaft which controls the valve, and thus controls the flow of water. Besides this, however, the construction just described has another important function—viz., that of indicating the proper time or distance for depositing the plants. In order to accomplish 125 this, I provide a gong or alarm L', and as the machine moves forward the knotted wire will at regular intervals engage the hammer of said bell, thus indicating to the person depositing the plants the proper interval or space.

It will be seen that the plow shown by me is arranged in the form of a wedge, both sides

spreading from the center alike, and that the water enters the furrow in the crotch of the plow. The plants are so placed in the crotch and the furrow filled by the side shoes. The 5 gathering-wings T T in front of the gage-wheel are for the purpose of gathering the soil in under the said wheel, thus making a firm ridge for planting.

Having thus fully described my invention, 10 what I claim, and desire to secure by Letters Patent of the United States, is—

1. In a transplanting-machine, the combination, with the frame thereof, of a water-tank or reservoir provided near its lower end with 15 a valve, a transverse shaft mounted in suitable bearings in the front of the frame, a rearwardly-extending rod or valve connected to said shaft, having its rear end passing through the valve, a bracket secured to one end of the 20 transverse shaft, a bracket secured to the rearmost member or arm provided with a series of perforations, an arm pivoted at or near its center to the forward member or arm of the bracket and provided on its rear end 25 with a perforation registering with the perforations in the bracket, a pin or bolt passing through said registering perforations, a lever pivoted to the end of said arm and having its rear end curved downwardly, and a drive- 30 wheel provided with a series of inwardly-extending pins constructed to engage the curved end of the lever, substantially as set forth.

2. In a transplanting-machine, the combination, with the frame, of an arm extending 35 inwardly from the same, a shaft pivotally connected to said arm, downwardly-inclined arms having outwardly bent or flaring lower ends, said ends being provided with gathering-wings, a yoke having the arms thereof extending on each side of the forwardly-extending arm, a transverse shaft having its bearings in said yoke and forwardly-inclined 40 arms, a gage-wheel mounted upon said shaft, and an adjustable ratchet-lever, substantially 45 as set forth.

3. In a transplanting-machine, the combination, with plow or runner supports, of adjustable angular brackets secured thereto, laterally-extending shoes secured to said adjustable brackets or to their equivalent, and a plow or runner secured between said supports, substantially as set forth.

4. In a transplanting-machine, the combination, with plow or runner supports, of angular brackets secured thereto, said brackets provided on their vertical members with elongated slots, transverse pins passing through said elongated slots and through perforations in the supports, whereby adjustability may be given, laterally-extending shoes secured to the horizontal members or arms of said brackets, and a plow or runner secured between the supports, substantially as set forth.

5. In a transplanting-machine, the combination of plow or runner supports, angular brackets secured thereto, said brackets provided on their vertical members or arms

with elongated slots, transverse pins passing through said elongated slots and through the perforations on the supports, whereby adjustability may be given, laterally-extending shoes secured to the horizontal members or arms of said brackets, and a plow having its rear end provided with an inclined or obliquely-extending piece and having its forward end provided with a series of perforations registering with the perforations in one of the sets of brackets through which one of the transverse pins may pass, substantially as set forth.

6. In a transplanting-machine, the combination, with plow or runner supports, of a plow or runner secured between said supports, and laterally-extending shoes secured to said supports, the outer edges of said shoes being 85 turned downwardly, so as to gather the earth into the furrow after the plant has been set, substantially as set forth.

7. In a transplanting-machine, the combination, with the frame thereof, of a reservoir or water-tank, a tubing extending therefrom, said tube provided near its lower end with a valve, a transverse shaft mounted in suitable bearings in the front of the frame, one end of the shaft being provided with a bifurcated 95 forwardly-extending arm, a rod having its rear end passing through the valve and its forward end secured to the rotatable transverse shaft, bearing-strips extending laterally from the side of the frame and having 100 rollers journaled therein, and a knotted wire extending from the forward roller into the bifurcated arm and thence over the rear roller, substantially as set forth.

8. In a transplanting-machine, the combination, with the frame thereof, of a reservoir or water-tank, a tubing extending therefrom, said tubing provided near its lower end with a valve, a transverse shaft mounted in suitable bearings in the front of the frame, one 110 end of said shaft being provided with a bifurcated forwardly-extending arm, a rod having its rear end passing through the valve and its forward end secured to the rotatable shaft, bearing-strips extending laterally from the 115 side of the frame and having rollers journaled therein, and a knotted wire extending from the forward roller into the bifurcated arms and thence over the rear roller, so as to turn the rotatable shaft with each engagement of 120 a knot with the bifurcated arm, substantially as set forth.

9. In a transplanting-machine, the combination, with the frame thereof, of a rotatable shaft extending laterally from said frame, a 125 forwardly-extending bifurcated arm secured thereto, a gong secured to the frame of the machine, and a knotted wire passing between the bifurcated arms and constructed to sound the alarm, substantially as set forth.

10. In a transplanter, the combination, with a reservoir having suitable tubing, said tubing provided with a valve, of a knotted wire constructed to operate said valve and let out

a quantity of water when such knot strikes the operating mechanism, substantially as set forth.

11. In a transplanter, the combination, with 5 the runner or plow, of a water-valve attached to said runner or plow and having its outlet at the heel of the plow, the plow with the attached valve working up and down with the unevenness of the ground, and a spring for

regulating the pressure upon and depth of the 10 plow, substantially as set forth.

In testimony that I claim the foregoing as my own I have hereunto affixed my signature in presence of two witnesses.

FRANK A. BEMIS.
